US00D834586S

(12) **United States Design Patent** (10) Patent No.: **US D834,586 S**
(45) Date of Patent: ** *Nov. 27, 2018

(54) **KEYBOARD**

(71) Applicant: **Apple Inc.**, Cupertino, CA (US)

(72) Inventors: **Jody Akana**, San Francisco, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Clement Tissandier**, San Francisco, CA (US); **Eugene Antony Whang**, San Francisco, CA (US); **Rico Zörkendörfer**, San Francisco, CA (US)

(73) Assignee: **Apple Inc.**, Cupertino, CA (US)

(*) Notice: This patent is subject to a terminal disclaimer.

(**) Term: **15 Years**

(21) Appl. No.: **29/606,501**

(22) Filed: **Jun. 5, 2017**

(57) **CLAIM**

The ornamental design for a keyboard, as shown and described.

DESCRIPTION

U.S. Design application Ser. No. 29/538,661 filed Sept. 4, 2015 is incorporated herein in its entirety by reference thereto.

FIG. 1 is a bottom front perspective view of a keyboard showing the claimed design;

FIG. 2 is a bottom top rear perspective view thereof;

(Continued)

FIG. 3 is a front view thereof;
 FIG. 4 is a rear view thereof;
 FIG. 5 is a left side view thereof;
 FIG. 6 is a right side view thereof;
 FIG. 7 is a top view thereof; and,
 FIG. 8 is a bottom view thereof.
 The broken lines in the figures show portions of the keyboard that form no part of the claimed design.

1 Claim, 6 Drawing Sheets

It is certified that error appears in the above-identified patent and that said Letters Patent is hereby corrected as shown below:

On the Title Page

In the Description, item (57), Line 6, please replace:
“FIG. 2 is a bottom top rear perspective view thereof;”
With:
“FIG. 2 is a top rear perspective view thereof;”

Signed and Sealed this
Sixteenth Day of April, 2019
